PIPE CUTTER

Thorvald Petersen, Erie, Pa.

Application August 3, 1953, Serial No. 26,260

Term of patent 14 years

(Cl. D54—13)

FIG. 2

FIG. 1

FIG. 3

FIG. 4

To all whom it may concern:

Be it known that I, Thorvald Petersen, have invented a new, original, and ornamental Design for Pipe Cutter, of which the following is a specification, reference being had to the accompanying drawing, forming a part thereof.

Fig. 1 is a front elevational view of a pipe cutter showing my new design, the device being shown in the open position.

Fig. 2 is a front elevational view of the pipe cutter, the device being shown in the closed position.

Fig. 3 is a top plan view of the pipe cutter.

Fig. 4 is a side elevation of the pipe cutter as viewed from the right of Fig. 2.

The dominant features of my new design are shown in solid lines.

I claim:

The ornamental design for a pipe cutter, as shown and described.
